UNITED STATES PATENT OFFICE.

JOSEPH BARRETT, OF NEW YORK, N. Y., ASSIGNOR TO SAMUEL W. DUNN.

DESIGN FOR OIL-CLOTHS.

Specification forming part of Design No. 8,273, dated April 20, 1875; application filed March 15, 1875.
[Term of Patent 3½ years.]

To all whom it may concern:

Be it known that I, JOSEPH BARRETT, of New York, county of New York, State of New York, have originated and designed a new Pattern for Floor Oil-Cloths, Carpets, or other fabrics, of which the following is a full, clear, and exact description, reference being had to the accompanying specimens or drawings, making part of this specification, and marked or designated as design No. 377, which is sufficient, without further aid, to enable any person skilled in the art to repeat it for practical use.

The colors employed for the different portions of this design may be varied to suit the convenience or taste of the manufacturer.

What I claim as my invention, and desire to secure by Letters Patent, is—

The design or pattern for floor oil-cloths or other fabrics, herein set forth.

JOSEPH BARRETT.
